United States Patent Office

Des. 183,425

Patented Aug. 26, 1958

183,425

PORTABLE CLEANING CART

Beatrice D. Grow, Warrington, Fla.

Application January 25, 1957, Serial No. 44,608

Term of patent 14 years

(Cl. D14—3)

FIG. 1.

FIG. 2.

FIG. 3.

FIG. 4.

FIG. 5.

FIG. 6.

FIG. 7.

FIG. 8.

Fig. 1 is a perspective view of a portable cleaning cart showing my new design;

Fig. 2 is another perspective view from a different vantage point showing my new design in another operative position;

Fig. 3 is a front elevational view of Fig. 1;

Fig. 4 is a right end elevational view of Fig. 3;

Fig. 5 is a rear elevational view of Fig. 1;

Fig. 6 is a right end elevational view of Fig. 5;

Fig. 7 is a top plan view of Fig. 3; and

Fig. 8 is a bottom plan view of Fig. 4.

I claim:

The ornamental design for a portable cleaning cart, substantially as shown.
